UNITED STATES PATENT OFFICE

BENNO SCHUBART, OF NUERMBERG, GERMANY, ASSIGNOR TO THE FIRM VEREINIGTE SCHUHFABRIKEN BERNEIS-WESSELS A. G., OF AUSBURG-OBERHAUSEN, GERMANY, A FIRM OF GERMANY

DESIGN FOR A BABY'S SHOE BOX

Application filed March 6, 1930, Serial No. 34,759, and in Germany November 16, 1929. Term of patent 7 years.

To all whom it may concern:

Be it known that I, BENNO SCHUBART, a citizen of the German Republic, residing at Nuremberg, Germany, have invented a new, original, and ornamental Design for a Baby's Shoe Box, of which the following is a specification, reference being had to the accompanying drawing, forming part thereof.

The figure is a perspective view of a baby's shoe box showing my design.

The ornamentation on the unseen side and end are each substantially the same as on the corresponding parts as illustrated.

I claim:

The ornamental design for a baby's shoe box, as shown and described.

Signed at Nuremberg, Republic of Germany, February 11, 1930.

BENNO SCHUBART.
